INSULATION FOR RAIL JOINTS

Edwards F. Schermerhorn, Brooklyn, N. Y., assignor to The Rail Joint Company, New York, N. Y., a corporation of New York

Application April 11, 1933, Serial No. 665,593

1 Claim. (Cl. 238—155)

This invention relates to means for insulating rail joints, and has particular reference to a novel and beneficial combination and assembly of an insulating end post interposed between the ends of the rails, and a head-piece of insulation interposed between the rails and the head of the splice bar.

In an insulated rail joint the head-piece of insulation usually is of substantially inverted L-shape in cross section to fit between the under-side of the rail head and the top of the splice bar and to extend downwardly a suitable distance between the inner side of the splice bar and the rail web, and for various different reasons it is 10 desirable that this head-piece of insulation shall be constituted by a single insulating member common to the end portions of both of the rails, rather than by two separate portions individual to the respective rails. If, however, the head-piece of insulation is constituted by a single insulating member having its top portion extending uninterrupted across the space between the ends of the rails, the sharp or burred corners at the ends of the rails, especially where the under faces 15 of the heads of the rails meet the end faces thereof, have a pronounced tendency, due to vertical and longitudinal movements of the rail ends, to cut into and to rupture and tear the insulation, thereby initiating a fracture or fractures. When a fracture begins it usually progresses from the point of cutting or rupture of the insulation diagonally to an adjacent bolt slot, which is the line of least resistance, and when such a fracture occurs there is a tendency for a 20 double fracture to develop, which may and frequently does result in a section of the insulation becoming broken away and dropping out of the joint, thus affecting the essential insulating capacity of the joint. Consequently, when a head-piece of insulation is constituted by a single insulating member common to the end portions of both of the rails, it is desirable to transversely slot the top portion of the member to provide a 25 gap therein for lateral alinement with the space between the rail ends, thereby to eliminate any possibility of the aforesaid sharp corners of the rails cutting into and initiating fractures in the insulation. However, while slotting of the top 30 portion of the insulating member eliminates one major disadvantage, it creates at the same time another problem inasmuch as an upwardly and outwardly opening pocket is produced between the splice bar and the rails into which metal cuttings, chips and the like from the rails and

other sources may collect and establish an electrical circuit between the rails.

Accordingly, the general object of the present invention is to provide, in combination with a head-piece of insulation constituted by a single member extending across the space between the ends of the rails, and having its top portion slotted in lateral alinement with the space between the rail ends, an end post of insulation having a formation to extend into and to fill the slot in the insulating head-piece, thus to obtain the principal advantages and at the same time to eliminate the objection to slotting of the insulating head-piece.

Another object of the invention is to provide 15 a novel headfree rail joint combination in which an end post of insulation has portions projecting between divided insulating head pieces of insulation and between shims interposed between the head pieces of insulation and the rails.

With the foregoing and other objects in view, which will become more fully apparent as the nature of the invention is better understood, the same consists in the novel features of construction, combination and arrangement of parts as 20 will be hereinafter more fully described, illustrated in the accompanying drawings and defined in the appended claim.

In the drawings, wherein like characters of reference denote corresponding parts in the different views:—

Figure 1 is a side elevation of a rail joint with the near splice bar removed and illustrating the present novel insulating combination.

Figure 2 is a central, transverse section through 35 the joint.

Figure 3 is a perspective view of the head-piece of insulation.

Figure 4 is a perspective view illustrating the head-piece of insulation and the insulating end post removed from the rail joint and assembled 40 with each other; and

Figure 5 is a view similar to Fig. 2 illustrating an alternative embodiment of the invention.

In the headfree, continuous type of rail joint 45 illustrated in the present instance, R, R, designate the headfree rails, B the splice bar, C the joint bolts, D an end post of insulation disposed between the ends of the rails, and E a head-piece of insulation interposed between the rails and 50 the head of the splice bar.

As will be noted by particular reference to Figs. 1 and 3 of the drawings, the insulating head-piece E is formed as a single member which is approximately coextensive in length with the rail 55

joint and which is of substantially inverted L-shape in cross section, the same being inclusive of vertically and laterally extending portions 10 and 11, respectively, joined together by 5 a rounded connecting portion 12. Thus, when the insulating head-piece is operatively embodied in the rail joint as shown, with the rounded portion 12 thereof interposed between the rail head fillet 13 and the upper inner corner 14 of the 10 splice bar, the vertical portion 10 of the insulation extends downwardly between the inner face of the splice bar and the webs of the rails and the lateral portion 11 thereof extends upwardly and outwardly between the top of the splice bar 15 and the rail head, whether the joint is of the well known standard type or is of the headfree type shown. In the portion 10, along the lower edge thereof, are formed recesses 15 to receive the joint bolts C whereby the insulation is held 20 against endwise movement, while formed in the lateral portion 11 medially thereof, or, in other words, in alignment with the space between the ends of the rails, is a transverse slot 16 which extends from the outer, upper edge of the portion 25 11 preferably inwardly across the rounded portion 12 and downwardly any suitable distance into the portion 10.

The slot 16 preferably is of a width corresponding to the normal width of the space between 30 the ends of the rails, whereby, as aforesaid, any danger of the sharp corners at the ends of the rails biting into the insulation and initiating the formation of a fracture or fractures is eliminated. Moreover, said slot preferably extends appreciably 35 downwardly into the vertical portion 10 of the insulation so as to provide, between its lower end and the lower edge of the insulation, a line of least resistance to fracture whereby, in the event of a fracture developing for any reason adjacent to the bottom of the slot, it will progress 40 along the line of least resistance and thus simply and without particular harm divide the insulation into two parts. However, as previously mentioned, the slot 16 produces, between the rails 45 and the head of the splice bar, an upwardly and outwardly opening pocket which, in the course of time and unless closed in some practicable manner, is liable to become more or less filled with metallic particles through which an electrical circuit may become established between the 50 rails.

Now, in accordance with the invention, and in order to provide a practicable means of filling or closing the slot 16 without affecting its functions, 55 the end post D of insulation which is interposed between the rail ends, and which in general outline conforms to the sectional shape of the rails, is formed with lateral extensions 17 from its web portion 18, and with downward extensions 19 from 60 its head portion 20 to enter and fill the slot 16. Thus, collection of metallic particles within the slot or pocket and any danger of a circuit being established between the rails due to this cause is effectively prevented.

Obviously, since closing of only the upper, open 65 end of the slot 16 is all that may be required to prevent foreign matter from entering the same, it is optional to provide the end post D with the extensions 17. Thus, only the upper or outer end 70 portion of the slot need be filled or closed, which may be accomplished by a downward extension

19 of minor length. Preferably, however, the slot is completely or substantially closed by the extensions 17, 19 which preferably are formed as a single, continuous extension, thereby completely safeguarding the joint against short circuits 5 due to the causes before mentioned.

According to the alternative embodiment of the invention illustrated in Fig. 5 the head insulation E' preferably is formed in two separate sections or, in other words, is divided at the meeting 10 ends of the rails R, although it may be formed in one piece, as shown in Fig. 3, and metallic shims S are interposed between said insulation and the rails, the said shims having formations S' which extend into the vacated areas at the 15 lower, outer corners of the headfree rails and at their under sides have bearing faces engaged by the laterally extending portions 11' of the insulation E'. The shims S also are formed in two separate sections or, in other words, are divided 20 at the meeting ends of the rails, and the end post D' of insulation is provided with lateral extensions 17' from its web 18' and with downward extensions 19' from its head 20' to enter and fill the spaces between the ends of the insulating 25 head pieces E' and the shims S. Thus, a very practical insulated and shimmed headfree joint is provided in which the load is transmitted to the splice bars B' not only through their upper, 30 inner corners but also through their heads outwardly of their upper, inner corners as in a standard joint.

Without further description it is thought that the features and advantages of the invention will be readily apparent to those skilled in the art, and it will of course be understood that changes in the form, proportion and minor details of construction may be resorted to, without departing from the spirit of the invention and scope of the appended claim. 40

I claim:—

An insulated rail joint comprising the rails of headfree section having the lower side portions of their heads sloping downwardly and inwardly, the splice bar, a one-piece head insulating unit 45 extending across the space between the rail ends and including a vertical portion disposed between the splice bar and the rail webs, a lateral portion disposed between the top of the splice bar and the bottom of the rail head adjacent to the head 50 fillet of the rail, and an upwardly and outwardly directed portion constituting an extension of the lateral portion and lying against the downwardly and inwardly sloping side portions of the rail heads, said unit having a slot opening 55 through the outer edge of the last mentioned portion thereof and extending inwardly through said portion and through the lateral portion downwardly into the vertical portion to a point spaced from the lower edge of the latter portion, and an insulating end post interposed between the rail 60 ends and having a lateral extension disposed in said slot, said end post extension substantially filling at least that portion of the slot which extends through the upwardly and outwardly directed portion of the insulating unit, the head of the splice bar having loading cooperation with the downwardly and inwardly sloping side faces of the rail heads through the upwardly and outwardly extending portion of the insulating unit. 65
